SEWER CLEANING DEVICE

George W. Kiesler, Sr., Barrington, Ill.

Application May 12, 1949, Serial No. 92,759

5 Claims. (Cl. 15—104.3)

1

The present invention relates to devices for cleaning sewers and is concerned primarily with a device that is adapted to cut away roots and other materials which grow and accumulate in the bore of a sewer with the ultimate result of clogging.

At the present time, such conduits as sewers, septic drains, and other tubular passages which are located in the ground are subject to having their conductive bores restricted by roots growing therewith and foreign material accumulating therein.

The present invention has in view, as its foremost object, the provision of a tool which is adapted to cut away such roots and remove the cut roots and any foreign material which may have accumulated in the bore of this sewer or drain.

More in detail, the invention has as an object, the provision of a tool, of the type indicated, which works on the principle of an auger. Thus, the tool includes, as an essential element, a main body member in the form of a helix which is provided with means at one end for securing an operating handle thereto and which carries at its other end cutting elements which are adapted to cut into roots under the influence of the rotating action of the tool.

When a tool of this type is inserted into the bore of a sewer, septic drain, or other comparable passage that is to be cleaned, and rotated, the helical body member will impart a forward motion to the tool causing it to feed into the sewer. At the same time, the rotating action causes the cutting elements at the forward end to cut into the roots and other accumulated matter. After an appropriate amount of the roots and such matter has been cut away, the tool may be withdrawn and it will bring with it these materials. In many instances, certain of the cutting elements will have cut into a root so as to form an interlock therewith, whereupon withdrawal of the tool will bring the whole root with it.

Various other more detailed objects and advantages of the invention such as arise in connection with carrying out the above noted ideas in a practical embodiment will, in part, become apparent, and in part be hereinafter stated as the description of the invention proceeds.

The invention, therefore, comprises a tool for cleaning out sewers and septic drains by cutting away roots and other foreign materials and which tool consists essentially of a helical body member in carrying cutting elements at one end and having means for attaching an operating handle to the other end.

2

For a full and more complete understanding of the invention, reference may be had to the following description and accompanying drawing wherein:

Figure 1 is an elevational showing of a tool designed in accordance with the precepts of this invention.

Figure 2 is a view in end elevation of the tool shown in Figure 1; and

Figure 3 is a view in side elevation of the end to which the handle is attached.

Referring now to drawing wherein like reference characters denote corresponding parts, and first more particularly to Figure 1, a tubular sleeve is shown at 10 and is formed with a slot 11 at one end and external threads 12 at the other. It is to this sleeve 10 that the operating handle (not illustrated) is to be attached through the medium of the threads 12. The length of this sleeve 10 will depend upon the particular character of the sewers or drains to be cleaned. If the sewers are fairly straight, the sleeve 10 may be fairly long in extent. On the other hand, if the sewers or drains should include curves, this sleeve should be made shorter to facilitate the taking of such turns.

A V-shaped yoke is defined by a pair of diverging legs 13 and 14 which are joined by a bend portion 15. This bend portion 15 is received in the slot 11 and permanently secured in this position as by welding, the latter being represented at 16. A helical main body member is referred to in its entirety by the reference character H and comprises a plurality of helical turns, the endmost turn at one end of said body member being designated 17 and the endmost turns adjacent the other end of said body member being designated 18 and 19.

The endmost turn 17 is preferably integrally joined to the leg 13 of the yoke as indicated at 20. The other leg 14 of the yoke is secured to this turn 17 diametrically opposite to the bend 20 as indicated at 21. This connection may be established in any preferred manner such as by welding.

The free end of the main body member H which is formed on the endmost turn 19 is formed as a cutting edge 22. Secured between the two endmost turns 18 and 19 and positioned longitudinally of the body member H is a cutting element 23 having a cutting edge 24 along one longitudinal edge thereof. This cutting element 23 may be secured in position in any preferred manner such as by the welds represented at 25 and 26.

Another cutting element 27 is arranged in a plane substantially normal to the plane of the

cutting element 23, and is positioned on the endmost turn 19, and is positioned transversely of the body member H. This cutting element 27 is connected in a bend of the outermost turn 19 as shown in Figure 2 and is preferably secured in this position as by welding. This cutting element 27 is formed with a cutting edge 28 located transversely of the body member H and cutting in the same direction of rotation as the cutting edge 24.

It is evident that the tool above described presents cutting edges in each of the three dimensions. Thus, regardless of the particular disposition of any root which may be located in the bore of a drain, definite assurance is had that one of the cutting edges 22, 24, or 28 will be properly located with respect thereto, so as to cut it away and permit of its removal. The cutting edge 22 is located transversely of the cutting edge 28 and cuts in the same direction of rotation as the cutting edge 24, and the cutting edge 28.

While the operation of the tool above described is believed to be obvious from the description given, it may be briefly summarized by noting that an appropriate operating handle is first attached to the sleeve 10 through the medium of the threads 12. The tool is now inserted into the bore of the sewer or drain to be cleaned with the turn 19 leading the way. As the tool is rotated under the influence of the operating member, the helical body H will cause it to feed forwardly. As roots or other foreign material are encountered, the cutting edges 22, 24 and 28 will cut thereinto. Whenever it is desired, the tool may be withdrawn and the materials so cut away will come out with the tool.

In many instances, one of the cutting edges will have become so imbedded in a root as to cause a firm interlock therewith. Thus, when the tool is withdrawn the whole root will come out with it.

After each withdrawal, the tool may be again inserted and the operation repeated until the entire sewer or drain is clean.

While a preferred specific embodiment of the invention is hereinbefore set forth, it is to be clearly understood that the invention is not to be limited to the exact constructions, mechanisms, and devices illustrated and described because various modifications of these details may be provided in putting the invention into practice within the purview of the appended claims.

What is claimed is:

1. In a tool for cleaning sewers, drains, and the like, a main body member consisting of a plurality of helical turns, the endmost turn at one end of said body member having a free edge formed as a cutting edge, and a cutting element arranged in a plane substantially normal to said cutting edge and across said endmost turn of said helical body member.

2. A tool for cleaning sewers, drains, and the like, comprising a body member made up of a plurality of helical turns, means for securing an operating handle to one end of said body member, a cutting element positioned longitudinally of said body member between the two endmost turns of said body member adjacent the other end thereof and secured thereto, said cutting element being formed with a cutting edge along one longitudinal edge thereof, and a second cutting element positioned on the endmost turn of said body member and transversely of said body

member at said other end thereof and secured thereto, said second cutting element being formed with a cutting edge thereon located transversely of said body member and cutting in the same direction of rotation as the first named cutting edge.

3. A tool for cleaning sewers, drains, and the like, comprising a body member made up of a plurality of helical turns, means for securing an operating handle to one end of said body member, a cutting element positioned longitudinally of said body member between the two endmost turns of said body member adjacent the other end thereof and secured thereto, said cutting element being formed with a cutting edge along one longitudinal edge thereof, and a second cutting element positioned on the endmost turn of said body member and transversely of said body member at said other end thereof and secured thereto, said second cutting element being formed with a cutting edge thereon located transversely of said body member and cutting in the same direction of rotation as the first named cutting edge, the free end of the endmost turn at said other end of said body member being formed with a cutting edge thereon located transversely of the second named cutting edge and cutting in the same direction of rotation as said first and second named cutting edges.

4. A tool for cleaning sewers, drains, and the like, comprising a body member made up of a plurality of helical turns, means for securing an operating handle to one end of said body member, and a cutting element positioned longitudinally of said body member between the two endmost turns of said body member adjacent the other end thereof and secured thereto, said cutting element being formed with a cutting edge along one longitudinal edge thereof, the free end of the endmost turn at said other end of said body member being formed with a cutting edge thereon cutting in the same direction of rotation as said first named cutting edge.

5. A tool for cleaning sewers, drains, and the like, comprising a body member made up of a plurality of helical turns, means for securing an operating handle to one end of said body member, a cutting element positioned on the endmost turn of said body member and transversely of said body member at the other end thereof and secured thereto, said cutting element being formed with a cutting edge thereon located transversely of said body member, the free end of the endmost turn at said other end of said body member being formed with a cutting edge thereon located transversely of the first named cutting edge and cutting in the same direction of rotation as said first named cutting edge.
